(57) **CLAIM**

The design for a cleaning device for optical connectors, as shown.

DESCRIPTION

FIG. 1 is a perspective view showing our new design.

FIG. 2 is a side elevation view thereof.

FIG. 3 is a side elevation view from the opposite side thereof.

FIG. 4 is a front elevation view thereof, the rear elevation being a mirror image thereof.

FIG. 5 is a top plan view thereof.

FIG. 6 is a bottom plan view thereof.

FIG. 7 is another perspective view thereof, wherein the cleaning device for optical connectors of our new design is shown in an alternate position of use; and,

FIG. 8 is a detail view of a portion of FIG. 7.
